TELEVISION SYNCHRONIZATION

Fritz Below and Johannes Günther, Berlin-Zehlendorf, Germany, assignors to the firm of Fernseh Aktien Gesellschaft, Zehlendorf near Berlin, Germany

Application August 10, 1938, Serial No. 224,095
In Germany August 17, 1937

7 Claims. (Cl. 178—69.5)

This invention relates to a method of synchronizing transmitters and receivers for television.

It is known in the art to transmit synchronizing impulses for synchronization of scanning wave generators in receivers with those at a transmitter, and to transmit such synchronizing impulses during periods in which no picture signals are transmitted. It is common practice to use the so-called retrace period for this purpose. It is also known to transmit two types of impulses for synchronization of the vertical and horizontal scanning generators, respectively, these impulses being of equal amplitude and differing merely in their duration. The duration of the synchronizing impulse for the vertical scanning, hereinafter referred to as the framing impulse, usually exceeds the duration of a scanning line by several times. Inasmuch as the horizontal or line scanning generator is preferably synchronized at the end of each line, also during the occurrence of the framing impulse, in order to avoid "drifting" of the horizontal scanning wave generator, special measures are necessary to secure line synchronization during this time. It has been proposed, for instance, to serrate a framing impulse at periodic intervals, and to insert line synchronizing impulses in the serrations, or to serrate the synchronizing impulses at periodic intervals and to synchronize the line scanning generators at one edge of the serrations.

These methods are difficult to make operate satisfactorily and involve considerable amount of apparatus.

It is the object of this invention to provide a simple and efficient method of frame synchronization avoiding the disadvantages of the above-mentioned methods, and to provide a simple means of impulse selection. Other objects and advantages of the invention will become apparent from the following.

The broad idea of this invention is to mix framing impulses of a duration in the order of one scanning line period with line synchronizing impulses of equal amplitude and polarity, but of considerably shorter duration; to apply this series of mixed impulses to a network possessing such frequency characteristics that the edges of the framing impulses will produce a peak opposite to the first mentioned polarity, and to utilize these peaks for synchronization of the vertical scanning generator at the receiver.

Referring to the drawing, Figure 1 shows a series of line synchronizing impulses interspersed with a framing impulse; Figure 2 shows the net-

work to which the series of impulses shown in Figure 1 is applied; Figure 3 shows the output of the network shown in Figure 2; Figure 4 shows the output of the same network for a slightly modified input; Figure 5 shows an amplitude selecting stage which selects the timing impulses for the vertical scanning generator.

The invention may now be explained in detail. Figure 1 shows a series of synchronizing impulses, the short impulses being for line synchronization, the impulse of longer duration a framing impulse. The line synchronizing impulses may have a duration of 10% of a line period, while the framing impulse extends over 150% of the line period. This may represent the signal available at the receiver after demodulation of the carrier if wirelessly transmitted. This signal is fed through a network as shown in Figure 2, comprising a capacitance 1 and a resistor 2. For television transmission at 441 scanning lines, 25 frames per second and an interlaced ratio of 2 : 1, and line synchronizing duration of 10% of a line period, the value of the capacitance 1 may be made approximately 1,000 micromicrofarads, and that of resistance 2 approximately 50,000 ohms. These values render a time constant at which the line synchronizing impulses will remain substantially undistorted when passing through the network. The framing impulses of longer duration, however, will become considerably distorted, as Figure 3 illustrates, which represents the output of the network according to Figure 2 taken across resistance 2. It may be seen that the trailing edge of the framing impulse of Figure 1 gives rise to a peak 3 in Figure 3, which can be used for synchronization of the vertical scanning generator. This peak impulse is of opposite polarity to the line synchronizing impulses so that discrimination between framing and line synchronizing impulses can be accomplished on the basis of difference in polarity.

For interlaced scanning, it is preferable to limit the duration of framing impulses to less than one-half scanning line period in order to avoid coincident occurrence of line synchronizing and framing impulses. This secures synchronization of the horizontal scanning generator without any of the special measures mentioned in the foregoing. The output of the network for framing impulses of a duration of less than one-half scanning line period is shown in Figure 4. Again the trailing edge of the received framing impulse produces an impulse. However, the immediately following line synchronizing impulse also pro-

duces an impulse in the same direction which differs from the first impulse only in amplitude. In this case it is, therefore, preferable, for perfect separation, to employ a discriminator circuit, for which an over-biased amplifier stage may be used. Such an arrangement is shown in Figure 5. The coupling condenser 1 and grid leak resistor 2 constitute the network shown in Figure 2. The output of the network is directly applied to the control grid or screen grid of an amplifier tube 4. The bias of tube 4 is so chosen that the tube does not draw current on the peak impulses caused by line synchronizing impulses. The plate circuit of tube 4 is capacitatively coupled to the vertical scanning generator 6 at the terminal 5.

It may be understood that networks other than that shown in Figure 2 may also be used to accomplish the same results. In fact, any network which substantially suppresses all frequencies below a frequency greater than the vertical scanning frequency, and lower than the horizontal scanning frequency, will produce the required results.

What we claim is:

1. In television, the method of synchronizing a scanning operation comprising the steps of transmitting a series of impulses of equal amplitude and polarity, certain impulses possessing a longer duration than others, applying said series of impulses to a network allowing the impulses of short duration to pass through said network substantially undistorted, and causing said impulses of longer duration to produce impulses having a polarity opposite to said first named polarity upon passing through said network, and utilizing only said impulses of opposite polarity to synchronize said scanning operation.

2. In television, the method of synchronizing a scanning operation comprising the steps of transmitting a series of impulses of equal amplitude and polarity, certain impulses possessing a longer duration than others, applying said series of impulses to a network allowing the impulses of short duration to pass through said network substantially undistorted, and causing said impulses of longer duration to produce impulses having a polarity opposite to said first named polarity upon passing through said network, applying the resultant series of impulses to a first scanning wave generator sensitive to impulses of one polarity only and applying the same resultant series of impulses to a second scanning wave generator sensitive to impulses of the opposite polarity only.

3. In television, the method of synchronizing a scanning operation comprising the steps of transmitting a series of impulses of equal amplitude and polarity, certain impulses possessing a longer duration than others, applying said series of impulses to a network allowing the impulses of short duration to pass through said network substantially undistorted, and causing said impulses of longer duration to produce impulses having a polarity opposite to said first named polarity upon passing through said network, applying the resultant series of impulses to a vertical scanning wave generator in such polarity that it responds to said impulses of opposite pol-

arity only, and applying said resultant series of impulses to a horizontal scanning wave generator in such polarity that it responds to said impulses of shorter duration only.

5 4. A television scanning system comprising a network including impedance elements and being adapted to have applied thereto a series of impulses of substantially equal amplitudes and of the same polarities, certain of said impulses having longer durations than others, said impedance elements being so proportioned as to permit passage through said network of the impulses of shorter duration substantially without distortion thereof and to render said network so responsive to said impulses of longer duration as to derive therefrom impulses having a polarity opposite to that of the applied impulses, and means for utilizing only said impulses of opposite polarity to synchronize scanning operations in said system.

10 5. A television scanning system comprising a network including impedance elements and being adapted to have applied thereto a series of impulses of substantially equal amplitudes and of the same polarities, certain of said impulses having longer durations than others, said impedance elements being so proportioned as to provide a time constant of the order of the duration of said impulses having longer durations, thereby to derive from said impulses of longer duration impulses having a polarity opposite to that of the applied impulses, and means for utilizing only said impulses of opposite polarity to synchronize scanning operations in said system.

15 6. A television scanning system comprising a network including capacitance and resistance elements connected in series relation and being adapted to have applied thereto a series of impulses of substantially equal amplitudes and of the same polarities, certain of said impulses having longer durations than others, said impedance elements being so proportioned as to permit passage through said network of the impulses of shorter duration substantially without distortion thereof and to cause said impulses of longer duration to develop across said resistance element impulses having a polarity opposite to that of the applied impulses, and means for utilizing only said impulses of opposite polarity to synchronize scanning operations in said system.

20 7. A television scanning system comprising a network including impedance elements and being adapted to have applied thereto a series of impulses of substantially equal amplitudes and of the same polarities, certain of said impulses having longer durations than others, said impedance elements being so proportioned as to permit passage through said network of the impulses of shorter duration substantially without distortion thereof and to cause said impulses of longer duration to develop across one of said impedance elements impulses having a polarity opposite to that of the applied impulses and initiated by the trailing edges of said applied impulses of longer duration, and means for utilizing only said impulses of opposite polarity to synchronize scanning operations in said system.
